UNITED STATES PATENT OFFICE

HAMILTON B. SPARKS, OF TERRE HAUTE, INDIANA

GEARING STRUCTURE FOR LATHES

Application filed July 21, 1930. Serial No. 469,553.

This invention appertains to lathes, and more particularly to a novel gear or transmission mechanism therefor.

One of the primary objects of my invention is to provide a novel reversing mechanism for the feed screw of the lathe which is of simple and durable construction and which can be readily and quickly actuated by the operator of the machine.

10 Another important object of my invention is the provision of a slide plate mounted on the head stock or bed of the lathe, having rotatably mounted thereon at spaced points gears of the idle type either of which upon manipulation of the plate is adapted to be moved into engagement with the opposite sides of a drive gear and in meshing engagement with the drive gears of the feed screw.

20 A further important object of my invention is the provision of novel means for operating the slide plate embodying a rock shaft mounted on the front of the lathe bed having an operating crank within convenient reach of the operation, the rock shaft being connected with the slide plate through the medium of a crank and pitman.

25 A further salient object of my invention is the provision of a swinging plate carried by the lathe carrying the drive gears for the feed screw with means for holding the plate in an adjusted position for bringing one of said drive gears into the path of the selected idle gear on the slide plate upon manipulation thereof.

30 35 A further object of my invention is the provision of novel means for forming the slide plate whereby gears of different diameters can be readily mounted thereon for permitting the changing of the speed of the feed screw.

40 A still further object of my invention is to provide an improved gearing for lathes of the above character, which will be durable and efficient in use, one that will be simple and easy to manufacture, and one which can be placed upon the market and incorporated with a lathe at a small cost.

45 50 With these and other objects in view, the invention consists in the novel construction, arrangement and formation of parts, as will

be hereinafter more specifically described, claimed, and illustrated in the accompanying drawings, in which drawings:

Figure 1 is an end elevation of a lathe showing my improved gear structure incorporated therewith. 55

Figure 2 is a fragmentary top plan view of a lathe showing my improved gear structure incorporated therewith.

Figure 3 is a horizontal section through the slide plate carrying the idle gears. 60

Figure 4 is a detail vertical section through the slide plate showing one of the idle gears carried thereby in meshing engagement with the spur gear of the stub shaft of the lathe. 65

Figure 5 is a top plan view of the swinging plate carrying the gears for the feed screw, a portion of the plate being shown broken away and in section to illustrate the adjustment thereof, and. 70

Figure 6 is a front elevation of the swinging plate with the various gears removed therfrom.

Referring to the drawings in detail, wherein similar reference characters designate corresponding parts throughout the several views, the letter A generally indicates a lathe which can be of any preferred or conventional construction and which embodies the lathe bed 10 having the usual head stock 11 for the drive spindle 12 thereof, which spindle may be driven in any preferred way. The spindle 12 at the outer end thereof is provided with a relatively small drive spur gear 13, which meshes with a relatively large spur gear 14, keyed or otherwise secured to the stub shaft 15 rotatably carried by the head block. Keyed to this stub shaft 15, is a relatively small spur gear wheel 16, which constitutes a part of the drive mechanism for 80

85 the feed screw 17 for the work. The bed of the lathe directly below the stub shaft 15 has secured thereto, in accordance with my invention upper and lower guide strips 20 and 21 which form guide tracks for slidably receiving the slide plate 22. The slide plate 22 carries a pair of spaced idle gears 23 and 24 which are of the same diameter and these idle gears 23 and 24 are rotatably mounted upon suitable stub shafts 25 bolted or otherwise 90

95

100

secured to the outer face of the slide plate. It is obvious that these gears can be readily removed to permit the replacing thereof by larger gears or smaller gears as the case may be to bring about the varying of the speed of the feed screw through the feed screw drive as will be later described. However, the proportion of the gears 24 and 23 relative to one another should remain the same at all times and it is to be noted that these gears are so disposed on the slide plate as to lie on opposite sides of the drive pinion or spur gear 16.

Rockably mounted on the feed screw shaft 17 is the swinging plate 26 which forms an important part of my invention. The swinging plate adjacent to the end thereof remote from the end rockably mounted on the screw shaft 17 is provided with an arcuate guide slot 27 through which extends a stud 28 carried by the frame of the lathe and this stud has threaded on the same a winged nut 29 for impinging against the swinging plate to hold the same any preferred adjusted position. Keyed or otherwise secured to the feed screw shaft 17 is a relatively large spur gear 30 and meshing with this gear is a spur gear wheel or pinion 31 rotatably mounted on a stub shaft 32 carried by the swinging plate. Directly above the spur gear 31 is a pair of meshing gears 33 and 34 of equal size and these gear wheels are rotatably mounted upon stub shafts 35 carried by said swinging plate 26.

It is obvious that by raising and lowering the swinging plate 26 that the gear wheel 33 and 34 can be brought into and out of the path of the gears 23 and 24 carried by the slide plate 22, for a purpose, which will be later described.

In order to bring about the effective sliding of the slide plate 22 I provide a bracket or extension plate 36 which can be bolted to the lathe bed 10, or frame so as to project laterally from the front edge thereof. This bracket or bed plate 36 carries suitable bearings 37 adjacent to its opposite end for the reception of a rock shaft 38. One end of the rock shaft is provided with a throw crank 39 to which is operatively connected the pitman rod 40. The pitman rod 40 is in turn connected by means of a suitable wrist pin or the like 41 to the slide plate 22. The opposite end of the shaft 38 from the end carrying the throw crank 39 is provided with a manipulating hand crank or lever 42, which lever carries a suitable manipulating handle 43.

The plate or bracket 36 can be provided with a resilient arcuate rack bar 44 for holding the operating crank 42 in its different adjusted positions.

In operation of my improved gearing, considering that the swinging plate 26 is in its raised position as shown in Figure 1 of the

drawings, when it is desired to rotate the feed screw 17 in one direction the crank 42 is moved to the right, Figures 1 and 2, which will slide the slide plate 22 to the right so as to bring the gear 23 carried thereby into meshing engagement with the spur gear 16 carried by the stub shaft 15 and the gear 33 carried by the swinging plate. Hence the drive from the spindle shaft 12 to the feed screw 17 is through the drive gears 13 and 14, the pinions 16, 23, 33, 34, 31, and 30, which will bring about the driving of the feed screw shaft in one direction. When it is desired to reverse the rotation of this feed screw shaft it is merely necessary to move the crank 42 to the left, Figure 1 of the drawings, which will slide the slide plate 22 to the left and thence bring about the meshing of the gear 24 carried by the slide plate with the pinion 16 and the pinion 34. Thus the drive will be through the drive gear 13 and 14, the pinions 16, 24, 34, 31 and 30.

It is obvious that by swinging the plate 26 downwardly that the drive gears can be brought out of the path of the gears 23 and 24 so as to stop the operation of the feed screw shaft, although the slide plate can be moved to an intermediate position so as to have the drive gears 23 and 24 both out of engagement with the pinion 16.

In order to bring about the effective changing of the speed of the feed screw shaft I prefer to make the swinging plate 26 as shown in Figure 6 of the drawings. As shown in Figure 6 the plate is provided with a pair of upper oppositely extending arcuate grooves 45 and 46, through which are adapted to extend the fastening means for the shafts 35 of the spur gears or pinions 33 and 34. Below the slots 45 and 46 is formed a third arcuate slot 47 which extends upwardly and toward the pivot thereof. By this arrangement of slots 45, 46 and 47 the shafts for the gears 33, 34, and 35 can be set in different positions so that different sized gears can be placed in intermeshing engagement with one another and with the gear 30 for bringing about the change of the gear speed ratio.

Changes in details may be made without departing from the spirit or the scope of this invention, but:—

What I claim as new is:

1. In a lathe, a spindle, a stub shaft, means for driving the stub shaft from the spindle, the stub shaft having a drive gear connected therewith, a feed screw, a gear keyed to the feed screw, a slide plate, a pair of idle gears rotatably carried by the slide plate and arranged on opposite sides of the drive gear carried by said stub shaft, means for operating the slide plate to bring either one of said idle gears in engagement with the opposite side of the gear carried by said stub shaft, a swinging plate, intermeshing gears rotatably carried by the swinging plate and meshing

with the gear on the feed screw shaft, and means for raising and lowering the swinging plate to bring certain of the gears carried thereby into and out of the path of said idle gears.

2. In a lathe, a reversing gear for the feed screw thereof including a swinging plate having a pair of upper oppositely extending arcuate slots and a lower arcuate slot extending upwardly and toward one end of the plate, said slots being adapted to adjustably receive stub shafts for idle gears.

3. In a lathe, a reversing mechanism for the feed screw thereof including a pair of guides connected with the lathe, a slide plate mounted in the guides, a pair of idle gears rotatably mounted on the slide of equal size, a supporting plate connected with the lathe, a rock shaft rockably mounted on the plate, means operatively connecting the rock shaft and slide plate including a crank and pitman, an operating crank for the rock shaft, and an arcuate rack bar having the teeth thereof arranged to engage the operating crank.

25 In testimony whereof I affix my signature.
HAMILTON B. SPARKS.
